UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

METAL CAR-DIAPHRAGM.

1,256,055.

Specification of Letters Patent. Patented Feb. 12, 1918.

Application filed March 25, 1916. Serial No. 86,618.

To all whom it may concern:

Be it known that I, HARRY H. SCHROYER, a citizen of the United States, and a resident of the city of Chicago, in the county of Cook and State of Illinois, have invented certain new and useful Improvements in Metal Car-Diaphragms; and I do hereby declare that the following is a full, clear, and exact description of the same, reference being had to the accompanying drawings, and to the numerals of reference marked thereon, which form a part of this specification.

This invention relates to an improved type of telescoping metallic car diaphragm consisting of only two sections, one of which is rigidly secured to the car body of a passenger coach and the other of which is adjustably mounted thereon adapted to move inwardly and outwardly and capable of lateral and vertical movements to a certain extent to permit adjustment of the diaphragm to take place when the same is connected to another diaphragm of a car 25 coupled to the car on which said metal diaphragm is mounted.

It is an object therefore of this invention to provide an improved diaphragm construction wherein a pair of telescoping sections are operatively connected with one another to permit one of said sections to move in telescoping relation both over and within the other during a contraction of the diaphragm.

It is also an object of this invention to construct a metallic car diaphragm consisting of a stationary section having flat vertical side walls and with a hood rigidly secured thereabove on the car comprising a top member flanged downwardly at its forward end and with another section, the side walls thereof overlapping the exterior of the side walls of the stationary section, and with the top member of the movable section flanged upwardly and adapted to slide beneath said downwardly flanged hood.

It is furthermore an important object of this invention to construct a sealed vestibule car diaphragm comprising a stationary and movable section slidably associated with one another and with the parts adjustably associated to permit warping movements therebetween.

It is finally an object of this invention to construct an improved type of metal car

diaphragm consisting of few parts easy to assemble and acting efficiently to form a weather-guarded passageway between two coupled cars equipped with diaphragms so constructed.

The invention (in a preferred form) is illustrated in the drawings and hereinafter more fully described.

In the drawings:

Figure 1 is a fragmentary central vertical section taken through the upper end of a vestibule diaphragm embodying my invention.

Fig. 2 is a detail section on line 2—2 of Fig. 1.

Fig. 3 is a detail section on line 3—3 of Fig. 1, with parts omitted.

Fig. 4 is a fragmentary detail section taken on line 4—4 of Fig. 1, with parts omitted and parts shown in elevation.

As shown in the drawings:

The reference numeral 1, indicates as a whole a car body on which is secured by means of rivets, brazing or other suitable means, an angle end beam or plate 2, which 80 arches over the vestibule opening at the end of the car. A stationary vestibule section is mounted on the car and comprises sheet metal side walls 3, each substantially of Z-section, and a metal top wall or ceiling plate 85 4. The top margins of said side walls are flanged inwardly and brazed or riveted to the under surface of the ceiling plate 4, as clearly shown in Fig. 2, affording an exceedingly rigid construction, and the inner- 90 most margins of said side walls, as clearly shown in Fig. 4, are riveted to upright I-beam frame members 5, forming a part of the car end.

A movable section of the diaphragm is 95 provided which is movable with respect to said first mentioned stationary section 3—4, and is supported in the usual manner of vestibule diaphragms upon an extensible portion of the car platform. Said movable 100 section of the diaphragm consists of flat sheet metal side walls 6, which at their upper ends are flanged horizontally inwardly, as denoted by the reference numerals 7, and an angled or gabled roof member 8, the 105 side margins 9, of which are bent inwardly, is fitted slidably over the inturned margins 7, of the side walls with a strip of sealing material 10, therebetween. The gabled roof member 8, at its forward margin is flanged 110

outwardly and bolted or riveted to a face plate 11, as clearly shown in Fig. 1, and the rear margin thereof is also flanged upwardly or outwardly, as denoted by the reference numeral 12. The side walls 6, of the movable section of the vestibule diaphragm are hingedly connected to the face plate 11, as clearly shown in Figs. 3 and 4, and for this purpose the forward margins of said side walls 6, are beaded over, as denoted by the reference numeral 13, and cut away at points intermediate the ends thereof to receive similar beaded portions 14, of hinge plates 15, which are bolted on the rear surface of the face plate, so that said pairs of registering tubular portions 13 and 14, may each receive a hinged pintle rod or bolt 16, inserted therethrough. Secured upon the hinge plates 15, are a plurality of springs 17, which bear upon the exterior of the side walls 6, to thrust the same inwardly toward one another in the slightly convergent relation shown in Fig. 4, and the inner ends of said side walls are provided with strips of sealing material 18, which bear in sealing relation on the exterior surfaces of the stationary side walls 3. Secured upon the upper front end of the car body 1, is an angled or gabled roof member or hood 19, the forward margin of which is flanged inwardly or downwardly, as denoted by the reference numeral 20, and the inner outturned margin 12, of the roof member 8, of the movable diaphragm section is adapted to slide beneath said hood 19, during adjusting movements of the diaphragm. Mounted upon the upper surface of the ceiling plate 4, is a compartment member comprising a top gabled wall 21, having vertical side walls integral therewith extending downwardly to the ceiling plate 4, and provided further with a front wall 22, and a rear wall 23. Extending slidably through said compartment member is a long rod 24, the forward end of which is secured pivotally on the rear surface of the face plate 11, and coiled about said rod is a compression spring 25, this mechanism being a well known construction for the upper end of vestibule diaphragms to resist telescoping movements of the parts.

The operation is as follows:

Many different types of metal diaphragm constructions have been designed wherein 55 telescoping side wall and roof members of stationary and movable sections are associated with one another, but the present invention differs advantageously from other diaphragms heretofore constructed in that 60 the roof member of the outer movable diaphragm section is provided with an outwardly or upwardly turned flange 12, which fits and moves beneath a stationary hood 19, having a forward downwardly turned flange 20. Thus a relative vertical move-

ment may take place between the stationary and movable diaphragm sections and the hood 12, with its downwardly turned forward margin prevents the admission of foreign matter upon that portion of the roof member 8, beneath the hood 19, between the flanged portions 12 and 20, so that adjusting movements of the diaphragm are not hindered.

Due to the hinged connection of the side 75 walls 6, with the face plate 11, it is obvious that pivotal movements of the face plate may readily take place, and of course the roof member 8, moves with said face plate, swinging in its compartment beneath the 80 hood 19, and only limited in such pivotal movement by the compartment or abutment member 21—22, the extreme width of which is considerably less than that of the diaphragm sections, as clearly shown in Fig. 85 2. Adjusting movements between the side walls 6, and the roof member 8, of the movable diaphragm section are readily permitted, due to the fact that the inturned respective flanges 7 and 9, thereof, have 90 sealing relation with one another with sealing means interposed therebetween secured on the flanged portion 9, of the roof member. Said side walls 6, are also permitted a sliding movement along the outer 95 surfaces of the stationary side walls 3, and in all positions of adjustment with respect thereto are sealed by the sealing strips 18.

I am aware that various details of construction may be varied through a wide 100 range without departing from the principles of this invention, and I therefore do not purpose limiting the patent granted otherwise than necessitated by the prior art.

I claim as my invention:

1. A metal vestibule diaphragm of the class described comprising a stationary section and a movable section adapted to telescope therewith, said stationary section comprising side walls, and a roof member, said roof member having an inturned downwardly directed flange, said movable section comprising adjustable side walls and a rigid roof member having an upwardly outwardly turned flange projecting beneath the 115 roof member of said stationary section, and sealing means disposed between the telescoping side walls of the diaphragm.

2. In a metal vestibule diaphragm of the class described, a stationary section comprising side walls, a roof member rigidly associated therewith, a movable section comprising hingedly mounted side walls adapted to be telescoped over said stationary side walls, a roof member adapted to slide beneath said stationary roof member, an upwardly outwardly turned flange on said roof member of the movable section projecting beneath the stationary roof member, a downwardly turned flange on said sta- 130

tionary roof member projecting over said roof member of the movable section, in-turned overlapping flanges on the movable section and movable roof member and a sealing material therebetween.

3. In a metal diaphragm, stationary side sections, a stationary roof section, hinged side sections adapted to telescope the stationary sections, a movable roof section, in-turned flanges at the end of the movable roof section, in-turned flanges at the top of the movable side sections, and a sealing strip between said flanges.

4. In a metal diaphragm, stationary side sections, a stationary roof section, hinged side sections adapted to telescope the stationary sections, a movable roof section, in-turned flanges at the end of the movable roof section, in-turned flanges at the top of the hinged side sections, a sealing strip between said flanges, and overlapping upwardly and downwardly directed flanges secured to the movable roof sections and the stationary roof section.

5. In a metal vestibule diaphragm of the class described, an inner stationary section, an outer movable section adapted to telescope therewith, said inner section comprising rigid side walls and a roof member, said movable section comprising hingedly mounted side walls adapted to slide over the exterior of said stationary side walls, a roof member adjustably associated with the hingedly mounted side walls adapted to slide beneath said stationary hood member, a forwardly downwardly turned flange on said stationary roof member, and an upwardly turned flange on said movable roof member to co-act therewith affording a closure between said stationary and movable roof members.

In testimony whereof I have hereunto subscribed my name in the presence of two subscribing witnesses.

HARRY H. SCHROYER.
